RAY EDWIN HALL, OF CHICAGO, ILLINOIS, ASSIGNOR TO HALL RESEARCH CORPORATION, A CORPORATION OF DELAWARE.

CIRCUIT-CONTROLLING MEANS.

Application filed August 13, 1919, Serial No. 317,118. Renewed February 24, 1923.

To all whom it may concern:

Be it known that I, RAY E. HALL, a citizen of the United States, and resident of Chicago, in the county of Cook and State of Illinois, have invented certain new and useful Improvements in Circuit-Controlling Means, of which the following is a specification.

My present invention relates more particularly to circuit changing devices especially adapted for use in place of a key or switch for transmitting wireless telegraph messages, but it will be obvious that it is capable of use in apparatus other than wireless and for purposes other than signalling. It comprises a resistance wire or filament, preferably platinum wire adapted to be heated, preferably to a high temperature, by flow of electric current therethrough, in combination with a cooling medium, preferably an air jet and means for operatively applying the cooling medium to cool the wire and lower its resistance, to produce the desired changes of current flow in the circuit controlled thereby.

The invention may be more fully understood from the following description in connection with the accompanying drawings, in which

Figure 1 is a diagram showing one form of my invention applied to a wireless telegraph sending system;

Figure 2 is a plan view of tape which is shown in edge view in Figure 1; and

Figure 3 is a detail view of a modified arrangement in which the jet is controlled by hand operated means instead of by tape.

In Figure 1 the usual elements of a wireless transmitting system operating by the spark discharge method are diagrammatically indicated as an alternating current generator 1, supplying currents to the transformer primary 2 which inductively energizes the secondary 3 which charges the condenser 4 discharging through spark gap 5 and creating oscillatory currents energizing the primary 6, which inductively energizes the secondary 7 in the radiating conductor 8.

As diagrammatically indicated in the drawings, the device comprises a filament 11, preferably of platinum wire and preferably arranged in an open coil so that a considerable length of it may be located in a small

space. The coil is serially connected in circuit with a source of electrical current which it is desired to control. The length and diameter of the coil is predetermined with reference to the maximum current flow in this circuit so that the current will normally tend to maintain the coil at high temperature. The filament is preferably of such small cross-section and such considerable length as may be attainable without danger of having it burned out by the maximum currents employed.

When properly proportioned to and heated by the current, the resistance of the wire or filament may be quickly and greatly lowered by application of a suitable cooling medium thereto, as for instance, air supplied through pipe 12 terminating in nozzle 13. When the air jet is discontinued, the current quickly reheats the wire to the maximum temperature thereby restoring the high resistance condition.

These changes of resistance may be controlled by controlling the application of the air jet to the hot wire in any desired way. Preferably the jet is fixed in position to discharge upon the coil and a movable member is arranged to be interposed to cut off the jet at desired intervals. For this purpose a hand operated key or lever 14 is shown in Figure 3 and a pattern tape 15 for the same purpose is shown in Figures 1 and 2.

The tape 15 may have long perforations 16, 16 and short perforations 17, 17 cut therein in proper relation corresponding to the dots and dashes representing letters of the Morse code, the groups representing the letters being suitably spaced apart. This tape is interposed between the nozzle 13 and the hot wire 11, and is drawn lengthwise at a desired, preferably uniform speed thereby exposing the hot wire to the blast for the required times, in the required sequence, and with the required intervals necessary for telegraphic transmission.

The pattern tape may be cut by special machinery operating on typewriter or other principles, so that it represents the message to be sent. Obviously, as many transcribers as necessary may be simultaneously employed in making the pattern tapes. Reels of such tape may be drawn lengthwise between the jet and the hot wire at any de-

sired speed by a simple mechanism diagrammatically represented by the feed rolls 18.

With the hot wire properly proportioned, 5 the cooling by the jet and the reheating by current, will be extremely rapid and in practice I find that the speed of sending by my present method may equal and in many cases exceed the speed at which the receiving op- 10 erator can work. By employing an automatic recorder at the receiving station, as for instance, the sensitive jet and interpreting relay described in my application Serial No. 301,010, filed May 31st, 1919, the capacity of a wireless telegraph system may be 15 very greatly increased.

Preferably the hot wire is enclosed in a casing 19 having an inlet 20 and an outlet 21 for the cooling medium. Such casing 20 serves to render the temperature changes of the wire independent of local temperature conditions.

In Figure 1 the specific form and arrangement of the circuit to be controlled 25 by the wire 11 is indicated as a shunt across the circuit from the alternating current generator 1, to the transformer primary 2. The device to be controlled by the resistance change in the wire 11 is another primary 30 winding 9, wound or connected in opposition to the primary 2 and adjusted so that when the wire 11 is cooled by the blast, the inductive effect on the secondary 3 of the currents flowing in primary 9 will be exactly 35 equal and opposite to the effect of primary 2. Hence there will be no current in secondary 3 and the radiating system will not be energized so long as the condition continues. Whenever the cooling medium is 40 cut off, the wire 11 quickly heats up and the greatly increased resistance will greatly decrease the neutralizing currents flowing in primary 9, and primary 2 being no longer neutralized, the secondary 3 will be energized, thus causing the condenser and spark 45 to function and the signal waves to be radiated from the aerial.

With the particular form of tape shown 50 in Figure 2, the received signals representing the message will be of a negative character, that is to say, the times between dots and dashes will be the times when energy is being radiated and received, the dots or dashes will be represented by times when no 55 energy is being radiated or received. This negative method of functioning is not im- 60 portant in its effect where the messages are recorded on tape at the receiving station but where a telephone receiver or other audible 65 indicator is employed, the result will be to have the dots and dashes represented by breaks or silences in an otherwise continuous note in the receiving telephone. This 70 is the reverse of the ordinary practice which 75 is to have the dots and dashes represented

by notes in the telephone and the times in between by silence. If the latter method is preferred, the method of cutting of the pattern tape may be reversed, the unperforated portions of the tape being then of 70 length corresponding to the dots and dashes and all of the rest of the tape being perforated.

The preferred arrangement described 75 herein involving the use of a third winding 80 acting as a bucking coil to neutralize the inductive action of the primary 2, is particularly advantageous because the changes 85 of resistance in wire 11, not only divert much of the current from the primary 2, but in addition they utilize that current so as to completely neutralize the remnant of 90 the current still flowing in primary 2. It is noted, however, that the range of resistance change in wire 11 may be very great and the amount of current thereby diverted from 95 the generator circuit may give enough decrease of current in the work circuit without the use of the bucking coil 9. In certain cases also it is possible to put the hot wire directly in series with the source and thereby cause variations sufficient for the purpose in view. These expedients are particularly applicable in direct current circuits or where batteries are used for the 100 source of current.

My temperature operated circuit controller may be also employed in many other known systems, as for instance, in wireless 105 telegraph systems which operate by sending out a continuous radiation and the signalling is effected by changing one or more of the tuning elements of the system. The wire 11 may be bridged around part or all of a tuning element or part or all of one 110 of the windings of the high frequency transformer.

As platinum wire may be had in any desired lengths and it is in diameters as small as .0001 inch, there is a wide range of selection to meet the particular purpose in view and for many purposes it may be found desirable to use a large number of short lengths of very fine wire in parallel with each other instead of a much longer wire 115 of larger diameter. The finer the wire the quicker it will heat and cool and the longer the wire the greater will be the resistance change in response to temperature variations.

The cooling medium may be a fluid other than air and the resistance filament may be a metal other than platinum. For instance, a fine iron wire might be used and in such case a hydrogen or nitrogen or other non- 120 oxidizing fluid may be employed as the cooling medium. The latter feature may be a disadvantage, but in certain cases, it may be more than compensated for by working the iron filament at the critical 125 130

high temperature range where small changes in temperature cause very great changes in resistance.

The air or other fluid used to cool the wire 5 may be refrigerated below the normal temperature of the surroundings, as for instance, gas or air stored at high pressure and refrigerated by expansion before conducting it to the jet. In most cases, how- 10 ever, this is unnecessary because in this way the temperature difference can seldom be increased more than 100 degrees or so and equivalent result can usually be attained more conveniently by working the hot wire 15 a hundred degrees or so nearer its melting point.

I claim:

1. In a wireless signalling apparatus, a transmitting system, including a high frequency oscillatory circuit in combination with means for supplying alternating current to said circuit, a transformer between said circuits, a circuit in shunt across the transformer, a circuit including a heat-sensitive resistance adapted to be heated to high temperature by current flowing in said shunt, and means for applying a cooling medium to said resistance and removing it therefrom according as maximum or minimum current is desired in said secondary circuit.

2. In the apparatus specified by claim 1, the further feature of a third winding for the transformer interposed in said shunt 25 circuit, wound and energized in a direction to countervail the current flowing in the primary winding of said transformer.

3. In the apparatus specified by claim 2, the further feature of having the resistance

of the shunt circuit of predetermined value 40 so that when the resistance is cooled and passing maximum current, the amount of said current flowing in said shunt circuit and through the third winding of the transformer will be sufficient to practically neutralize the current flowing in the primary 45 of said transformer.

4. A circuit controlling resistance, comprising a solid heat sensitive conductor, means for heating it to high temperature by 50 electric currents flowing therein, means for applying a cooling jet to said conductor to lower its resistance and means including a movable member for controlling the time and duration of such application. 55

5. A circuit controlling resistance, comprising a solid heat sensitive conductor, means for heating it to high temperature by 60 electric currents flowing therein, means for applying a cooling jet to the said conductor to lower its resistance and means including a movable pattern for controlling the time and duration of such application.

6. A circuit controlling resistance, comprising a solid heat sensitive conductor, means for heating it to high temperature by 65 electric currents flowing therein, means for applying a cooling jet to the said conductor to lower its resistance and means for controlling said jet, said means including a perforated tape and means for feeding the same between the jet and the heat sensitive conductor to alternately interrupt and permit discharge of the jet on the conductor. 70

Signed at Montreal, in the Province of Quebec and Dominion of Canada this 8 day of August, A. D. 1919. 75

RAY EDWIN HALL.
